UNITED STATES PATENT OFFICE

111,295

DESIGN FOR A STORE FRONT

Raymond E. Smith, Joliet, Ill.

Application April 14, 1937, Serial No. 68,745

Term of patent 14 years

To all whom it may concern:

Be it known that I, Raymond E. Smith, a citizen of the United States, residing at Joliet, in the county of Will and State of Illinois, have invented a new, original, and ornamental Design for Store Fronts, of which the following is a specification, reference being had to the accompanying drawing, forming a part thereof.

Fig. 1 is a front elevation of a store front showing my new design, and

Fig. 2 is a vertical, central, sectional view taken along the line 2—2 of Fig. 1.

I claim:

The ornamental design for a store front, substantially as shown.

RAYMOND E. SMITH.
